UNITED STATES PATENT OFFICE

2,079,170

HIGHWAY FLARE

James H. Horsley, Chicago, Ill., assignor to
Shanklin Manufacturing Company, Chicago,
Ill., a corporation of Illinois

Application February 10, 1936, Serial No. 63,107

4 Claims. (Cl. 67—55)

The present invention is directed to portable flares of the liquid fuel burning type adapted for use on vehicle highways and railroad right of ways as a caution to or as a warning for operators of approaching vehicles of impending danger.

A primary object of my invention resides in the provision of certain novel constructional features wherein a plurality of flares may be superimposed in nested stack formation and mounting them on 10 a suitable support for carrying on a truck, bus or other vehicle, for convenient use when occasion necessitates.

Another object is to provide each of a group of 15 nested flares with an individual closure adapted for encompassing the burner, for extinguishing the flame, preventing escape of fumes, and to prevent vaporization and leakage of the liquid fuel when the flare is not in use.

A further object of this invention resides in the 20 provision of novel means for yieldingly securing a plurality of superimposed nested flares together as a unit, for convenience in placing them in or removing them from a suitable support on a vehicle and serving as a handle for carrying the 25 entire group of flares.

With the foregoing and other objects in view which will appear as the description proceeds, the invention consists in certain novel features of 30 construction, arrangement and combination of parts hereinafter fully described, illustrated in the accompanying drawings, and particularly pointed out in the appended claims, it being understood that various changes in the form, proportion, size and minor details of the structure 35 may be made without departing from the spirit or sacrificing any of the advantages of the invention.

For the purpose of facilitating an understanding of my invention, I have illustrated in the 40 accompanying drawings, a preferred embodiment thereof, from an inspection of which when considered in connection with the following description, my invention, its mode of construction, assembly and operation, and many of its advantages should be readily understood and appreciated.

Referring to the drawings in which the same characters of reference are employed to indicate corresponding or similar parts throughout the 50 several figures of the drawings:

Figure 1 is a view in side elevation of a plurality of nested flares mounted on a support constructed in accordance with the present invention;

Fig. 2 is a front view of the entire unit with

parts broken away to illustrate details of construction;

Fig. 3 is a top plan view of assembled device;

Fig. 4 is a transverse sectional view taken substantially as indicated at line 4—4 of Fig. 2;

Fig. 5 is a fragmentary elevational view of a flare, with the closure cap separated from the burner; and

Fig. 6 is a vertical section through the supporting bracket for the stack of flares.

Due to the increasing relatively heavy vehicular traffic on highways, particularly adjacent large metropolitan areas, the stoppage of large vehicles, such as trains, busses, and trucks, on or near the highway at night is a serious menace 15 to operators of other vehicles traveling along the highway. If operators of such stopped vehicles would place suitable portable flares on the highway adjacent the stopped vehicle, many accidents could be avoided. The present invention contemplates the provision of a novel arrangement of a plurality of nested flares which may be suitably carried on the vehicle and which may be conveniently brought into use when occasion arises.

The flares embodying the present invention are of the liquid fuel burning type, and each includes a container body 5, herein shown as of cylindrical form, having its top wall formed with a neck defining a mouth in which is threadedly connected or otherwise secured thereto the shank of a burner 6 having a cylindrical base 7 seated against the top wall of the container. The burner is provided with a wick 8 extending into the liquid fuel in said container body for supplying fuel to the burner in a manner well understood in the art.

When the flare is not in use, a cup shaped closure cap 10 is mounted over the burner and detachably secured thereto by engagement of a cam slot 10a adjacent its bottom, with a co-operative projection 7a on the base of the burner, as may be seen in Fig. 5 of the drawings. This cap may be employed to extinguish the flare, to ensure sealing of the fumes therein, and to prevent vaporization and leakage of the liquid fuel. The lower edge of the cap, when in assembled position is adapted to contact a gasket 12 of suitable sealing material disposed around the cylindrical base 7 of the burner 6, as shown in Fig. 2 and Fig. 5. By virtue of this construction, each flare of a group is wholly individual in that it may be used independently without exposing the burners of other flares.

For convenience, I have herein illustrated a

stack of three nested flares, but it will be manifest that the stack may be composed of any desired number of units. The bottom wall of each container body 5 is formed to provide a centrally located re-entrant cavity 5^a, dimensioned to receive therein the burner 6 and closure cap 10 of the next lower flare of the stack with the bottom wall supported directly upon the top wall of said next lower flare. This arrangement centralizes the units and maintains them in aligned stack formation, and contact between the top and bottom walls serve as a further seal.

The uppermost flare is provided with an auxiliary protector cap 15 having a cup-shaped portion 15^a encompassing the burner closure cap 10 and having an annular flange 15^b with a resilient gasket 16 interposed between said flare and the top wall of the container body 5. All of the flare units are resiliently connected together as a unit by means including a pair of upwardly extending side members 18, slotted at 18^a at their lower ends for detachable securement to hook members 19 carried on the side wall of the body 5 of the lowermost flare, a bail member 20 positioned above the uppermost flare and having offset shoulders 20^a seated on top and engaging opposite sides of the annular flange 15^b of the protecting cap. The terminal portions of said bail are connected by coil springs 22 to the upper ends of the side members 18. When it is desired to connect the group of nest flares together, the bail 20 is seated, as seen in Fig. 2, and the side members 18 drawn downwardly, tensioning springs 22 and secured on the hook members 19. The upper portion of the bail is of inverted U-shape formation and serves as a handle for lifting and conveniently carrying the entire group of flares. The lowermost portion of each of the side members 18 is bent substantially at right angles as shown in Fig. 2, to provide a suitable finger engaging portion 18^a, and which may be pressed upon by the operator to cause a disengagement of the hook member 19 from the slot 18^a.

The assembled group of nested superimposed flares may be mounted on a suitable supporting bracket, as indicated at 25, located at any convenient place on the vehicle, such as the driver's cab of a bus or truck. The bracket includes an upright member 26 which may be secured as by screws 27 to a vertical surface and rigidly connected to the lower portion of said member 26 is a circular flanged foot 28 on which the nested flares are supported. Connected to the upper end of said member 26 is a horizontally extending resilient finger 30 adapted to be engaged by the top of the bail when the group of flares are mounted on the support for yieldingly maintaining them in position. Said resilient finger 30 and aligned portion of the bail are provided with registering apertures 30^a and 20^b, respectively, for receiving the shackle of a padlock to prevent tampering and unauthorized removal of the flares from the support.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. A plurality of superimposed flares, each including a container body having an upwardly projecting wick carrying burner, and a closure cap detachably connected to the burner and engaging the top of the container body for sealing the burner from atmosphere, predetermined container bodies each having their bottoms formed with a re-entrant cavity for receiving the burner and cap of the next lower flare, whereby said flares may be nested in a stack, with the burner and enclosing cap of each lower flare projecting into the cavity of the body of the next upper flare, and yieldable means for maintaining said flares in nested relation, said yieldable means comprising a pair of hangers, having finger engaging portions formed at their lower edges, and means coacting with the lowermost container body for detachably holding the flares in nested position, and a bail extending over and engaging the body of the uppermost flare, having its lowermost portions secured to the upper portions of said hangers by coil springs.

2. A plurality of superimposed flares, each including a container body having an upwardly projecting wick carrying burner and a closure cap detachably connected to the burner and engaging the top of the container body for sealing the burner from atmosphere, predetermined container bodies each having their bottoms formed with a re-entrant cavity for receiving the burner and cap of the next lower flare, whereby said flares may be nested in a stack with the burner and enclosing cap of each lower flare projecting into the cavity of the body of the next upper flare, and means for securing said flares together as a unit in nested relation, said means including a pair of upwardly extending side members detachably connected to the body of the lowermost flare, a bail extending over and engaging the body of the uppermost flare, and coil springs connecting the ends of said bail to said side members, said side members having their lowermost portions bent substantially at right angles to form finger engaging pieces for facilitating in the disassembly of the flares.

3. A plurality of superimposed flares, each including a container body having an upwardly projecting wick carrying burner, and a closure cap detachably connected to the burner and engaging the top of the container body for sealing the burner from atmosphere, predetermined container bodies each having their bottoms formed with a re-entrant cavity for receiving the burner and cap of the next lower flare, whereby said flares may be nested in a stack with the burner and enclosing cap of each lower flare projecting into the cavity of the body of the next upper flare, means for securing said flares together as a unit in nested relation, said means including a pair of upwardly extending side members detachably connected to the body of the lowermost flare and having their lowermost portions bent substantially at right angles to form finger engaging pieces, a bail extending over and engaging the body of the uppermost flare, and coil springs connecting the ends of said bail to said side members, and a support for said nested stack of flares, including a resilient finger adjacent its upper end positioned to be tensioned by engagement with said bail, when the assembled unit of flares is mounted on the support to yieldingly maintain them in position thereon.

4. A plurality of superimposed flares, each including a container body having an upwardly projecting wick carrying burner, and a closure cap detachably connected to the burner and engaging the top of the container body for sealing the burner from atmosphere, predetermined container bodies each having their bottoms formed with a re-entrant cavity for receiving the burner and cap of the next lower flare, whereby said flares may be nested in a stack with the burner and enclosing cap of each lower flare projecting into the cavity of the body of the next upper flare, a protecting member for the uppermost flare including a cup-shaped portion enclosing the cap of said flare and having a transverse

flange seated on the body of said upper flare, and means for securing said flares together as a unit in nested relation, said means including a pair of upwardly extending side members detachably connected to the body of the lower flare and having their lowermost portions bent substantially at right angles to form suitable finger engaging pieces, a bail extending over the body of the uppermost flare and having offset portions seating upon the flange of the protecting member, and coil springs connecting the ends of said bail to said side members to yieldably maintain the said flares in nested position.
